By Myself James Murphy*

UNITED STATES PATENT OFFICE.

JAMES MURPHY, OF CHICAGO, ILLINOIS, ASSIGNOR TO THE PROVIDENT FURNACE COMPANY, OF SAME PLACE.

DESIGN FOR A FURNACE-TILE.

SPECIFICATION forming part of Design No. 34,585, dated May 28, 1901.

Application filed January 12, 1901. Serial No. 43,078. Term of patent 14 years.

To all whom it may concern:

Be it known that I, JAMES MURPHY, a citizen of the United States, residing at Chicago, in the county of Cook and State of Illinois, have invented and produced a new and original Design for a Furnace-Tile, of which the following is a specification, reference being had to the accompanying drawings, forming part thereof.

10 Figure 1 is a view in perspective of a furnace-tile embodying my new and original design; Fig. 2, a broken vertical section taken as indicated at line 2 of Fig. 1; and Fig. 3, a horizontal section taken as indicated at line

15 3 of Fig. 1.

As shown in the drawings, the leading or

material feature of my design consists of a tile A of rectangular cross-section, having a vertical air-passage a close to the outer wall of the tile, a perforation a', perpendicular to the passage a and opening at the lateral surfaces of the tile, and a downwardly-inclined orifice a², which opens at the inner or fire surface of the tile.

What I claim as new, and desire to secure 25 by Letters Patent, is—

The design for a furnace-tile herein shown and described.

JAMES MURPHY.

In presence of—

D. W. LEE,

ALBERT D. BACCI.
